United States Patent Office

Des. 220,620
Patented May 4, 1971

220,620

LOUNGE

Eugene F. Jones, 941 Reed Ave.,
East Point, Ga. 30344

Filed Dec. 17, 1969, Ser. No. 20,528

Term of patent 14 years

Int. Cl. D6—01

U.S. Cl. D15—11

Fig. 5

Fig. 5

Fig. 2

Fig. 4

FIG. 1 is a perspective view of a lounge showing my new design.

FIG. 2 is an end view of one end.

FIG. 3 is the top plan view of the lounge shown in FIG. 1.

FIG. 4 is an end view the other end of that shown in FIG. 2.

FIG. 5 is a side elevation of the view of the lounge shown in FIG. 1.

The side of the lounge not shown is a mirror image of the side shown.

I claim:

The ornamental design for a lounge, as shown and described.
